(57) **CLAIM**

The ornamental design for a rolled product container, as shown and described.

DESCRIPTION

FIG. 1 is a top perspective view of a rolled product container in a closed condition in accordance with the present teachings.

FIG. 2 is a bottom perspective view of the rolled product container of FIG. 1.

FIG. 3 is a first side view of the rolled product container of FIG. 1.

FIG. 4 is a second side view of the rolled product container of FIG. 1.

FIG. 5 is a third side view of the rolled product container of FIG. 1.

FIG. 6 is a fourth side view of the rolled product container of FIG. 1.

FIG. 7 is a top view of the rolled product container of FIG. 1.

FIG. 8 is a bottom view of the rolled product container of FIG. 1.

FIG. 9 is a top perspective view of a rolled product container in an open condition in accordance with a second embodiment of the present teachings.

FIG. 10 is a bottom perspective view of the rolled product container of FIG. 9.

FIG. 11 is a first side view of the rolled product container of FIG. 9.

FIG. 12 is a second side view of the rolled product container of FIG. 9.

FIG. 13 is a third side view of the rolled product container of FIG. 9.

FIG. 14 is a fourth side view of the rolled product container of FIG. 9.

FIG. 15 is a top view of the rolled product container of FIG. 9; and,

FIG. 16 is a bottom view of the rolled product container of FIG. 9.

The broken lines shown represent portions of the rolled product container that form no part of the claimed design.

1 Claim, 8 Drawing Sheets
